UNITED STATES PATENT OFFICE

133,037

DESIGN FOR AN ANTLANDING DEVICE FOR PIGEONS

Samuel Kraus, New York, N. Y.

Application May 19, 1941, Serial No. 101,013

Term of patent 14 years

To all whom it may concern:

Be it known that I, Samuel Kraus, a citizen of the United States and resident of New York city, in the county of New York and State of New York, have invented a new, original, and ornamental Design for an Antilanding Device for Pigeons, of which the following is a specification reference being had to the accompanying drawing, forming a part thereof.

Fig. 1 is a side elevational view of an antilanding device for pigeons, showing my new design.

Fig. 2 is a top plan view of the same.

Fig. 3 is a bottom plan view of the same.

The characterizing features of my design for an anti-landing device for pigeons reside in the antilanding elements shown, arranged upon a screw support having a head portion of the specific configuration shown.

I claim:

The ornamental design for an antilanding device for pigeons, substantially as shown and described.

SAMUEL KRAUS.
